UNITED STATES PATENT OFFICE.

ARTHUR J. SMITH, OF NEW YORK, N. Y.

HAIRPIN.

1,313,750.

Specification of Letters Patent.

Patented Aug. 19, 1919.

Application filed May 7, 1919. Serial No. 295,286.

To all whom it may concern:

Be it known that I, ARTHUR J. SMITH, a citizen of the United States, residing at New York, in the county of New York and 5 State of New York, have invented new and useful Improvements in Hairpins, of which the following is a specification.

An object of the invention is to produce 10 a hair pin, which like some pins now in use, is made up from a single piece of resilient material but differing from the other pins in that the pin is made up from a single piece of resilient material of uniform cross sectional dimension, except at one point 15 only.

Another object of the invention is to produce a hair pin, which, as stated, is like some hair pins now in use, consisting of 20 undulated prongs extending from the "bight" or upper curved portion, in approximately parallel relation. But the "bight" is the only point at which the material from which the hair pin is constructed is not of the same uniformity, and at which 25 point the material is flattened so as to reduce to a minimum the deterioration now experienced in the use of pins. The prongs of the pins are brought together to assume their normal position with respect to each 30 other, regardless of the number of times that the pin is put to use.

Another object of the invention is to produce a pin which may be easily inserted in the hair to give the desired effect, that 35 is, to hold the strands of hair in place at all times and hence a slightly and neat coiffure is the result. The simplicity of the construction is what makes it possible to manufacture the pins in great quantities at a 40 low cost, as it requires but a very simple operation to flatten each pin at the proper point, moreover, the twisting and bending at the "bight" of the pin is obviated.

With the above and other objects in view 45 which will appear as the nature of the invention is better understood, the same consists in the improved construction and novel arrangements of parts which will herein-after be fully described and particularly 50 pointed out in the claim.

In the accompanying drawings, has been 55 illustrated, a single and preferred form of the invention, it being, however, understood that no limitation is necessarily made to the precise structural details therein exhibited, but that changes, alterations and modifi-

cations within the scope of the claim may be resorted to when desired.

In the drawings:

Figure 1 is a side elevation of the hair pin. 60

Fig. 2 is an enlarged side elevation of the upper portion thereof.

Fig. 3 is a sectional view taken on the line 3—3 of Fig. 2.

Fig. 4 is an end elevation. 65

Referring to the drawing in detail it will be seen that I have shown a pin of very simple design. The numeral 1, designates a single piece of resilient material such as wire, of any desired kind. The wire is bent 70 to provide prongs 2—2, which extend from the upper curved portion or "bight," designated by the numeral 3. The prongs 2—2, are each provided with crimps or convexities 4—4. The convexities of one prong 75 oppose the convexities of the other prong, as clearly shown in the drawing, and the purpose of which will be hereinafter explained. The lower extremities of the prongs 2—2 are curved outwardly as at 5 80 to permit of the ready insertion of the pin into the hair.

In the construction, the pin is pressed or pinched to give to the "bight" 3, a flattened portion, as at 6. 85

Aside from the mentioned flattened portion 6, the wire from which the pin is constructed, is uniform throughout. The convexities of the prongs 2—2 which oppose each other, are brought together to form loops 90 for the strands of hair. The hair, or strands thereof are made to pass into the loop so formed and with but a slight manipulation of the pin. The hair, in passing into the loops only temporarily spreads 95 the prongs the flexing or spreading action occurs along the prongs. The flexing in the plane of the prongs does not occur at the "bight" owing to the flattened portion which has the tendency to cause the prongs 100 to retain their original and normal relation.

The flattened portion 6, in the preferred form, is formed by pinching the inner portion only of the bight, leaving the outer portion with its original curvature as seen 105 in Fig. 3 and giving the bight a cross section which is substantially T-shaped. This renders the bow or bight of the pin round on the exterior so that it has the usual appearance when employed in the hair, and 110 avoids the presence of edges or corners on the exterior which may injure the operator's

fingers or a hair ribbon or hat. Moreover it is well known that structural members of T-shaped cross section have greater strength than those which are nearly flat, and resist bending both laterally and edgewise. Therefore by pinching or compressing the inner side of the bow or bight and leaving the outer side of its original formation, I gain the combined advantages mentioned.

10 What I claim is:

The herein described hair pin whose

prongs and bight are formed of wire round in cross section throughout, excepting that the inner side of the bight is flattened or compressed so as to render it thin and narrow between the inner faces of the prongs and leave it rounded on its outer face, for use as substantially hereinbefore set forth. 15

In testimony whereof I have affixed my signature.

ARTHUR J. SMITH.
